UNITED STATES PATENT OFFICE.

WILLIAM W. ARNOLD, OF DAYTON, OHIO.

PROTECTOR FOR CHECKS.

1,201,235.

Specification of Letters Patent.

Patented Oct. 17, 1916.

Application filed February 1, 1915. Serial No. 5,360.

To all whom it may concern:

Be it known that I, WILLIAM W. ARNOLD, a citizen of the United States, residing at Dayton, in the county of Montgomery and State of Ohio, have invented certain new and useful Improvements in Protectors for Checks, of which the following is a specification, reference being had therein to the accompanying drawing.

10 This invention relates to protectors for checks and the like and more particularly to devices of this kind which mark upon the check the amount for which it is drawn or a certain maximum amount, for which 15 the check will be honored, thus preventing the raising of the check above the amount marked thereon, the marking being of such a character that it cannot be altered.

The object of the present invention is to 20 provide in a protector an organization of mechanism in combination with a casing characterized by great compactness without sacrificing efficiency and which can be operated by hand quickly and easily.

25 In the accompanying drawings, Figure 1 is a side elevation of a protector embodying my invention, with part of the casing broken away; Fig. 2 is a top, plan view with part of the casing removed; Fig. 3 is a sectional view taken on the line *a—a* of Fig. 1 and looking in the direction of the arrows; Fig. 4 is a detail view of the feeding device; Fig. 5 is a detail view of the adjustable marking device or type wheel; and Fig. 6 35 is a detail view of the casing.

In these drawings I have illustrated one embodiment of my invention and have shown the same as comprising two parts movably connected one to the other and normally spaced apart to receive between them a check or other instrument in writing upon which it is desired to place a permanent mark. These members are of such a character that they can be grasped in one hand 45 and operated to cause one member to move toward the other. One of the members is provided with an adjustable marking device, such as a type wheel, which can be quickly adjusted to bring any one of a series 50 of marks or figures into marking position. The other member is provided with a device to take an impression from the marking device, such as a platen, which is so arranged with relation to the type wheel or 55 marking device that when movement is imparted to one of the members the paper will

be moved into engagement with the marking device and an impression taken therefrom. Further, the device is provided with feed mechanism which is automatically actuated by the relative movement of members to feed the paper forward step by step, thereby permitting a series of different figures or marks to be placed thereon. Means are provided for moving the feeding mechanism into an inoperative position to permit of the insertion of the check and this means is of such a character that it can be actuated by the hand which grasps and operates the two members of the device. The two members of the device and their co-operating parts may be of various constructions and may be operated in various ways and that form of the device here shown has been chosen for the purpose of illustration 75 because it has been found to be very efficient.

In the particular embodiment of the invention here illustrated the two members of the device are shown at 1 and 2, respectively, and are pivotally connected one to the other 80 at points between their ends and are provided with extensions 4 and 3 forming handles, by means of which the two members may be actuated. The two members are normally spaced apart and are held in this 85 position by means of a spring. As here shown, the two members intersect and are connected by means of a pivot pin 5 extending through the intersecting or bearing portions thereof. One of these bearing portions is provided with an annular groove 6 in which is arranged a spring 7 extending about the pivot pin and connected at its opposite ends to lugs 8 and 9 carried by the respective members. The arrangement of 90 the spring is such that the tension of the same tends normally to separate the two members and the lugs are so arranged that they will be brought into engagement by the action of the spring and will thus tend 95 to limit the movement of the two members under the influence of the spring. The member 1 carries the greater portion of the mechanism and is provided with a two part casing, the main portion, 10, of which carries the marking device and the removable portion, 11, of which forms a closure for the fixed portion and carries the feeding device.

The marking device may be of any suitable character and may be such as to print, emboss, perforate or otherwise place a per-

manent mark on the paper. In the present instance the marking device is shown as comprising a type wheel 12, the type of which are preferably of metal and are serrated so that they will not only print on the paper but will emboss therein a series of lines or serrations so arranged as to form the figures. This character of type, however, is well known in devices of this kind and does not form a part of the present invention. The type wheel is provided with the numerals 0 to 9 and with the dollar mark and such other characteristics as it may be desired to use in connection with the marking of the check or other paper. This type wheel is mounted on a shaft 13, one end of which is journaled in a boss 14, formed on the inner side of the portion 10 of the casing and forming a bearing for that end of the shaft, and the other end of which extends through and is rotatably supported by the portion 11 of the casing. That end of the shaft 13 which extends beyond the portion 11 of the casing is provided with a knurled head 15 by means of which the type wheel may be rotated. Suitable means are provided to hold the type wheel in its adjusted positions and this means is here shown as comprising a series of recesses 16 formed in one side of the type wheel and adapted to receive a spring-actuated detent, such as a sprung-pressed ball 17 carried by the part 11 of the casing. The recesses and detent have correspondingly tapered sides which serve not only to hold the type wheel in its adjusted position but also serve to center the same so that the selected type is in correct printing position. Inasmuch as the selected type, from which the impression is to be taken, is not readily visible I prefer to provide in connection with the type wheel an indicator which will be readily visible to the operator and will indicate which type is in printing position. As here shown the type wheel is provided with a lateral extension 18 provided on its periphery with figures and marks corresponding to the type on the type wheel and arranged to be visible through a sight opening 19 in the part 10 of the casing. The figures on the indicator 18 are so arranged with relation to the type on the type wheel 12 that the particular figure which is visible through the sight opening will correspond with the type which is in printing position. Thus, by manipulating the knurled head of the shaft 13 the type wheel can be quickly and accurately adjusted to cause any desired mark to be made. A suitable inking device is provided in connection with the type wheel and, as here shown, this inking device comprises a rotary ink pad or drum 20 journaled in the part 11 in the casing adjacent to the type wheel and held in yielding engagement therewith. As here shown the ink pad is

carried by a shaft 21 which is journaled in the ends of a pair of spring arms 22 mounted at their lower ends upon the casing and arranged to hold the pad yieldingly in engagement with the type wheel but to permit the same to rotate with the type wheel. Preferably, the casing is provided with an opening 23 to enable the pad to be reinked without disassembling the device as a whole. This opening is normally closed by a spring clip 24.

The member 2 of the device consists, in the present instance, merely of an arm having at its forward end an impression-taking device, such as a platen 25, arranged to move the paper against the particular type which is in printing position, this operation being secured by the manipulation of the handles 3 and 4.

As has been stated the two members of the device are normally spaced apart by the action of the spring so that the check or other paper can be readily inserted between them. I have, however, provided a support for the check and, as here shown, the casing as a whole is provided with a longitudinal slot 26 formed in that portion thereof between the lowermost portion of the type wheel and the central impression position of the platen or impression-taking device. This slot is open along three sides and the portions of the casing adjacent to one end of the slot are formed apart so as to form a guide which will cause the check to be very readily inserted in the slot in a position to receive the mark. A feeding device is provided to advance the check or other paper step by step after the marking of each mark thereon and this feeding device is preferably actuated by the relative movement of the two members of the protector. Thus, after the check has been placed in proper position in the slot 26 it requires no further attention on the part of the operator. He sets his marking device to make the desired mark on the paper, operates the protector to make this mark and then adjusts his marking device to make the next mark which it is desired to place upon the paper, the operation of the device to the marking of the first-mentioned mark having served to feed the paper forward one step, the position to receive the next mark. In the present instance the feeding mechanism is carried by the part 11 of the casing, the lower portion of which is provided with a chamber to receive the same.

The feeding mechanism may be of various kinds but it preferably consists of feeding rollers and, in the present instance, I have shown a feeding roller 27 journaled in the part 11 of the casing above the slot 26 and have shown a second feeding roller 28 journaled in the part 11 of the casing below the slot 26 and adapted to extend into the slot 26.

to press the paper which has been inserted therein against the upper feed roller 27. This lower feed roller is here shown as formed in two parts but this is not a necessary feature of its construction. One of the rollers and, in the present instance, the lower roller is movable relatively to the other roller so as to permit the two rollers to be separated to enable the check to be placed in the slot. In the present instance, the lower roller is journaled on a crank shaft 29 and a spring 30 tends to move the same upward toward the roller 27. To enable the roller 28 to be moved downward against the tension of the spring 30 I have provided a lever 31 journaled in the casing and having at one end an arm 33 provided with a finger 34 extending across the shaft 29 above the spring 30 and between the two parts of the roller, whereby the movement of the lever about its axis in one direction will cause the finger 34 to press down on the shaft and thus carry the roller away from the upper roller 27, thereby leaving the slot 26 unobstructed for the insertion of the check. The outer end of the lever 31 is in the form of a finger 35 which is placed exteriorly of the casing and is arranged in such a position that it can be engaged by the thumb or finger of the hand which grasps the protector, thereby enabling the operator to open the slot to receive the check and then release the check after it has been marked, by the use of one hand, leaving the other hand free to handle the check. The upper roller 27 is preferably the one that is actuated to feed the paper and, to this end, it is provided with a ratchet wheel 36 which is rigidly secured thereto and is adapted to be engaged by a spring-pressed pawl 37 mounted on the member 2 of the protector which is provided with a projection or finger 38 to support the same. The pawl and ratchet are so arranged that the movement of the two members one toward the other will not actuate the feed roller but the separation of the two members after the marking has been accomplished will actuate the upper feed roller and cause the paper to be advanced. A second pawl 39 acts as a detent to hold the feed roller against backward movement during the upward movement of the feed pawl 37.

The operation of the device will be readily understood from the foregoing description and it will be apparent that the device is small and compact, is readily portable and will mark the check as efficiently as will the non-portable devices. The device can be carried in the pocket if desired. In the present instance it is designed more particularly for desk use and is intended to be kept in a drawer or carried in a satchel. Consequently, the handles 3 and 4 are unobjectionable but it is obvious the movable member could be operated without the use of the long handles 3 and 4. The mechanism is very simple and positive in its operation and is of such a character that it can be produced at a low cost. Further, it will be noted that the two members of the device are formed in three parts which can be readily cast, thus simplifying and cheapening the construction.

Having thus fully described my invention, what I claim as new and desire to secure by Letters Patent, is:—

1. In a device of the character described, a casing having a longitudinal slot therein to guide and support an article to be printed, said casing having a handle fixed thereto, a marking device rotatably mounted within said casing above said slot, an inking device journaled in said casing above said slot and on an axis parallel to the axis of said marking device, means to hold said inking device in engagement with said marking device, and a second rigid one piece handle pivoted to said first-mentioned handle and projecting into said casing below said slot, the projecting end of said second handle constituting a platen to coöperate with said marking device to cause a mark to be placed on the article. 75
2. In a device of the character described, a casing having a longitudinal slot therein to guide and support an article to be printed, said casing having a handle fixed thereto, a marking device rotatably mounted within said casing above said slot, a second rigid one piece handle pivoted to said first-mentioned handle and projecting into said casing below said slot and said marking device, the projecting end of said handle constituting a fixed platen to coöperate with said marking device to cause a mark to be placed on the article, a feeding device comprising coöoperating feed rollers mounted in said casing laterally of said marking device and the projecting end of the second handle, one of said rollers being mounted below said slot and the other of said rollers being mounted above said slot, and means operable by the relative movement of said handles to actuate said rollers to feed the paper. 90
3. In a device of the character described, a casing having a longitudinal slot therein to guide and support an article to be printed, said casing having a handle fixed thereto, a marking device rotatably mounted within said casing above said slot, a second handle pivoted to said first-mentioned handle and projecting into said casing below said slot and marking device, feeding rollers actuated by the relative movement of said handles to feed said paper, said rollers being mounted within the casing and laterally of said marking device and the projecting end of the second handle and arranged 105

- one above and the other below said slot, one of said rollers being capable of bodily movement toward and away from the other, and a lever pivotally mounted on said casing to the rear thereof and to one side of said handles to move said bodily movable roller away from the other roller.
4. In a device of the character described, a two part casing having a longitudinal slot therein to guide and support an article to be printed, one part of said casing having a marking device rotatably mounted therein above said slot, a handle fixed to said part, and a second handle pivoted to said first-mentioned handle and projecting into the first part of said casing below said slot and marking device, the projecting end of said second handle comprising a rigid fixed portion and having a platen fixed thereto to cooperate with said marking device to cause a mark to be placed on the article, feeding rolls mounted in the second part of said casing, one of said rolls being mounted above and the other below said slot, means on said second handle cooperating with said rolls to actuate the same to feed the article, and means mounted on the casing to the rear thereof and to one side of said handles to bodily separate said rolls.
5. In a device of the character described, a casing having a longitudinal slot therein to guide and support an article to be printed, said casing having a marking device rotatably mounted therein above said slot, a handle fixed to said casing, a second handle pivoted to said first handle and projecting into said casing below said slot and marking device, the projecting end of said handle constituting a platen to cooperate with said marking device to cause a mark to be placed on the article, feeding devices mounted in said casing to one side of said marking device, and means slidably and resiliently mounted upon said second-mentioned handle to operate said feeding devices at each operation of said second-mentioned handle.

In testimony whereof, I affix my signature in presence of two witnesses.

WILLIAM W. ARNOLD.
